UNITED STATES PATENT OFFICE.

ARTHUR BESSEY SMITH, OF EVANSTON, ILLINOIS, ASSIGNOR TO AUTOMATIC ELECTRIC COMPANY, OF CHICAGO, ILLINOIS, A CORPORATION OF ILLINOIS.

SWITCH CONTROL CIRCUIT FOR AUTOMATIC TELEPHONE SYSTEMS.

Application filed September 19, 1919. Serial No. 324,997.

To all whom it may concern:

Be it known that I, ARTHUR BESSEY SMITH, a citizen of the United States of America, and a resident of Evanston, in the county of Cook and State of Illinois, have invented certain new and useful Improvements in Switch Control Circuits for Automatic Telephone Systems, of which the following is a specification.

10 My invention relates in general to control circuits for automatic switches, but more particularly to such circuits as extend over long aerial lines, or which include a section of cable, and which therefore have considerable electrostatic capacity; and the object of 15 the invention is to provide an improved circuit arrangement wherein the effect of line capacity is neutralized, thereby permitting automatic switches to be controlled accurately and certainly.

I have shown in Fig. 1 of the drawing that embodiment of the invention which I consider to be the best; and in Figs. 2 to 7, inclusive, I have shown certain modifications of the invention which produce the desired results more or less perfectly in somewhat different ways. The modifications shown in Figs. 6 and 7 are not claimed herein, but are claimed in my divisional application Serial No. 603,934, filed November 29, 20 1922.

Referring to Fig. 1, the reference character L indicates a line of high electrostatic capacity, and which may be a so called simplex circuit superimposed on a toll or long distance line. R' is a relay adapted to be energized by the closure of the switch S and which may thereafter be intermittently deenergized by operation of the calling device D to produce a series of interruptions in the circuit of the line L. This circuit includes at the opposite end of the line the relay R² which responds upon the initial closure of the line circuit to complete a switch control circuit over conductors L' and L², and which deenergizes thereafter responsive to interruptions in the line circuit to reproduce such interruptions in the switch control circuit.

50 Circuits corresponding to those described above are well known in the art. Relay R' may be a relay of a repeater located in a particular exchange, which repeater is accessible to calling subscribers for enabling

them to establish connections over the toll line with which the repeater is associated; while relay R² may be a relay of another repeater at the opposite end of the toll line, whose function it is to control one or more automatic switches to complete such connections to the desired called lines, all of which is well understood, as previously stated.

I will now proceed to explain the operation of my invention. Referring to Fig. 1, and neglecting for a moment the condenser C and battery B², or rather, assuming that they are not present, it will be seen that when relay R' is energized, the negative pole of grounded battery B' is connected to line L, thereby causing a current flow over the said line and resulting in the energization of relay R² at the distant end. At the same time, the line conductor may be said to become charged negatively by reason of its electrostatic capacity with regard to the earth. Now when relay R' is momentarily deenergized to interrupt the circuit, current flow from the battery will cease and relay R² should instantly deenergize. However, still assuming the absence of condenser C and battery B², it does not do this, but remains energized for an instant after its circuit is broken thereby prolonging obviously its periods of energization and diminishing its periods of deenergization, to the great detriment of the controlling impulses transmitted over the circuit. This faulty operation is due to the charge on the line, which at each interruption of the circuit flows off through the relay R² to ground and thus holds the said relay energized for an instant after each interruption, or more generally speaking, renders it sluggish in responding to interruptions of the circuit.

Consider now the effect of condenser C and battery B² connected as shown in Fig. 1. While relay R' is energized the condenser is short-circuited and therefore completely discharged. Now when the relay R' deenergizes and interrupts the line circuit, the condenser is connected from the line to the positive pole of grounded battery B², from which it will appear that the negative charge on the line will flow into the condenser, in a manner of speaking, and charge it, this action being assisted by the fact that the opposite side of the condenser is connected to the positive pole of the grounded battery,

instead of direct to ground. It will thus be seen that the condenser affords a means for dissipating the line charge, whereby a large portion of it is prevented from flowing thru the relay R^2 to ground. Relay R^2 becomes much more quickly responsive to interruptions in its circuit and the process of transmitting switch controlling impulses is rendered certain and dependable.

10 Taking up the modifications now, these will be easily understood without extended explanation. Fig. 2 shows means for directly grounding the line circuit between interruption, which is found to be helpful in certain cases. The arrangement shown in Fig. 3 resembles that shown in Fig. 1 in that a condenser is used which is short-circuited while the line circuit is closed and which is connected from the line to ground during interruptions. No battery is used however, in connection with the condenser. In Fig. 4 a battery of reversed polarity operates directly without the interposition of a condenser to take care of the line charge. With this arrangement a rather high resistance must be used to prevent the reverse current flow from rising to too high a value before the end of the interruption of the line circuit. An improvement on this idea, Fig. 5, uses a relay of low resistance which on operating inserts a high resistance in series with its own winding to limit the current flow. Fig. 6 may be considered an improvement on Fig. 3. A condenser is connected from the line to ground during interruptions of the line circuit, as in Fig. 3; but when the line circuit is closed the condenser is oppositely charged instead of merely being short-circuited. The condenser therefore, need only be half as large. The last modification, Fig. 7 uses a condenser oppositely charged but dispenses with the extra battery, the circuit arrangement being such that during closures of the line circuit the condenser is oppositely charged by the main battery.

Other modifications than those pointed out above will doubtless occur to persons skilled in the art; and the invention will no doubt be found to be of utility under circumstances differing from those specifically mentioned. I do not, therefore, wish to be held to the exact form of the invention disclosed herein, but desire to include and have protected by Letters Patent all variations thereof which come within the scope of the appended claims.

What I claim as my invention is:

1. In a telephone system, a ground return line circuit having a relay at one end responsive to direct current, said line having high electrostatic capacity, two batteries at the other end, one battery having the positive pole grounded and the other the negative, both batteries being directly connected

to the ground, means for connecting said batteries in the line circuit alternately, one battery being effective to cause energizations of said relay and the other battery being effective to discharge the line and thereby assist said relay to deenergize, and a non-inductive resistance in series with the second battery between the battery and the line:

2. In a telephone system, a ground return line circuit having a relay at one end responsive to direct current, said line having high electrostatic capacity, two batteries at the other end, one battery having the positive pole grounded and the other the negative, means for closing the line circuit thru one battery to operate said relay, means for intermittently interrupting the circuit to produce deenergizations of said relay, means for closing the line circuit thru the said other battery each time the circuit is interrupted to discharge the line, and a resistance in series with said second battery to prevent said relay from energizing.

3. In a telephone system, a ground return line circuit having a relay at one end, said line having high electrostatic capacity, two batteries at the other end, one battery having the positive pole grounded and the other the negative, means for closing the line circuit thru one battery to operate said relay, means for intermittently interrupting the circuit to produce deenergizations of said relay, a condenser, means for connecting the line by way of said condenser to the said other battery to discharge the line each time the circuit is interrupted, and means for discharging said condenser each time the circuit is closed.

4. In a telephone system, a line circuit including a relay, a condenser, said line circuit normally connected through said condenser to a battery of one polarity at the end opposite the relay, and means for switching said end of the line circuit into connection with a battery of the opposite polarity to energize said relay and for short circuiting said condenser to dissipate the charge collected from the line.

5. In a telephone system, a line circuit including a first relay, a condenser, a second relay for controlling said line circuit in response to impulses, said second relay maintaining said line circuit connected through said condenser to a battery of one polarity normally to discharge the line circuit, and energized to short circuit said condenser and to connect the line circuit to a battery of another polarity to energize said first relay.

6. In a telephone system, a line circuit including a relay, a condenser, means for sending impulses of current over said line circuit from a battery of one polarity and for connecting said line circuit through said con-

- denser to a battery of the opposite polarity to remove the charge from the line circuit between impulses, and additional means for discharging said condenser during impulses. 5
7. In a telephone system, a line circuit including a relay, batteries of opposite polarity, a condenser, means for sending impulses of any desired duration from one of said batteries over said line circuit to operate said relay, and for connecting said line circuit through said condenser to the other battery between impulses to assist in the de-energization of said relay. 10
15. 8. In a telephone system, a ground return line circuit having a non-polarized relay at one end normally responsive to continuous current in either direction, two batteries at the other end, one battery having the positive pole grounded and the other the negative, means for connecting said batteries in the line circuit alternately, one-battery being effective to cause energizations of said relay and the other battery being effective to re-20 verse the current in the line to cause the relay to deenergize quickly, and means for preventing said relay from again energizing while the current is reversed. 25
9. In a telephone system, a ground return line circuit having a non-polarized relay at one end normally responsive to continuous current in either direction, two batteries at the other end, one battery having the positive pole grounded and the other the negative, means for closing the line circuit through one battery to operate said relay, means for interrupting the circuit to produce deenergizations of said relay, means for closing the line circuit through the sec-30 ond battery each time the circuit is interrupted to reverse the current in the line and thereby cause said relay to deenergize more quickly, and a resistance in series with said second battery to prevent the said relay from energizing while the current is reversed. 35
10. In combination, a ground return line circuit including a relay at one end, a battery, a condenser, and a second relay at the other end of the line, means for energizing and deenergizing said second relay, and contact springs controlled by said second relay for closing the line circuit through said battery and for short-circuiting said condenser when the relay is energized, and for con-40
- necting the line to ground through said condenser when the relay is deenergized. 45
11. In combination, a line circuit terminating in a relay at one end, a battery at the other end, a second relay and means for energizing it to connect said battery in the line circuit to energize said first relay, means for intermittently deenergizing said second relay to produce interruptions in the current flow, a condenser, means for temporarily connecting said condenser in shunt of said first relay to discharge the line each time said second relay deenergizes, and means for short-circuiting said condenser to discharge it each time said second relay energizes. 50
12. In combination, a ground return line circuit having a relay included at one end and a battery at the other, means for intermittently interrupting the line circuit to operate said relay, a condenser, a shunt path from the line to ground through said condenser, means for opening said shunt when the line circuit is closed and for closing it to discharge the line each time the line circuit is interrupted, and means comprising a shunt circuit excluding any current source for discharging the condenser each time the line circuit is closed. 55
13. In combination, a line circuit includ-60 ing a battery at one end and a relay at the other end, a condenser, a charge collecting circuit including said line and condenser but excluding said battery, a discharge circuit for said condenser excluding said relay and said battery, and a relay having contact springs for closing the line and discharge circuits when energized and the charge collecting circuit when deenergized. 65
14. In combination, a line circuit includ-70 ing a battery at one end and a relay at the other end, a condenser, a charge collecting circuit including said line and condenser but excluding said battery, a discharge circuit for said condenser excluding said relay and said battery, and a two position electro-75 magnetic switch having contacts for closing said line and discharge circuits in one position and said charge collecting circuit in the other position. 80
